UNITED STATES PATENT OFFICE.

THEODORE S. MORTON, OF ST. LOUIS, MISSOURI.

REFRIGERATOR.

Application filed April 22, 1926. Serial No. 103,688.

This invention relates to refrigerators and has for its object to provide an article of this character having double walls, between which a high degree of vacuum is maintained.

A further object is an arrangement of waste pans in which the said pans are enclosed within the walls which constitute the casing, and outside atmosphere is prevented 10 from access to the ice chamber through the vent pipe as is ordinarily the case.

Another feature of the refrigerator is a means to take up the overflow from one waste pan; and the fact that while the one 15 pan is removed for emptying; the other is still in position to catch the drip, thus preventing any water from splashing in the chamber, or running out of the casing and on to the floor of the room.

These and other objects will be fully described in the following specification, and illustrated in the accompanying drawings; in which:

Fig. 1 shows a front view of the refrigerator.

Fig. 2 shows a vertical section on the line 2—2 of Figure 3.

Fig. 3 shows a plan section on the line 3—3 of Figure 1.

Fig. 4 shows an enlarged fragmentary view on the line 4—4 of Figure 3.

Referring to Figure 1 of the drawings; a casing 10 rests upon the feet as shown at 11 and 12. Secured to this casing in the usual 35 way, are doors as shown at 13, 14, 15, etc. Now, referring to Figure 2, it will be seen that an inner wall 16, is held in position within the casing 10 by means of the blocks as shown at 17, 18, 19, etc.; other blocks are 40 indicated by the dotted lines 20, 21, etc.; these, while preferably of cork, may be of any suitable material. In the space 22 between the inner and outer walls the atmosphere is exhausted to produce a sufficient degree 45 of vacuum to insure the required insulation against the warm outside air. The efficiency of vacuum casings as applied to bottles and like devices is well known and requires no detailed description here. A vertical partition 23 divides the refrigerator centrally; and compartments as shown at 24, 50 25 etc. are provided for the storage of food stuffs.

The ice compartment 26, in which is shown 55 a cake of ice 27; has a sloping bottom 28 which inclines toward a central vent 29.

This vent discharges the waste water into the drip pan 30 which rests upon a rack 31 having cross members as that shown at 32 in Figure 4 of the drawings. The drip pan 30 is provided with a hinged side wall 33 and a flexible lining; preferably of rubber as shown at 34 in Figure 4.

Referring now to Figure 4; it will be seen that the wall 33 has a protruding lip 35 and a rod 36 secured therein. A yoke lever 37 having a slotted extremity 38 is mounted on the shaft 39, which is supported in suitable bearings on the floor member 40. This shaft is provided with the spring 41 shown 70 in Figure 3, which serves to maintain the yoke lever in its upper position where it acts to hold back the wall member 33. A hand lever 42, shown best in Figure 2, serves as a means for rotating the shaft 39 when it is 75 desired to discharge the water from the drip pan into the lower basin as shown at 43.

The lining 34; when in closed position; folds at the corners as shown at 44. An overflow aperture 45, is provided at the center of the flexible wall as shown in Figure 4, and water as indicated at 46 may; when at sufficient height flow therethrough into the lower basin.

Hand grips 47 and 48 are provided on the 85 beveled portions of the pans to facilitate their removal when required.

The doors are all provided with vacuum chambers as shown at 49 and 50.

While I have shown and described the 90 preferred embodiment of my invention; I do not wish to be held to these exact details of form and construction, but claim the right to such minor modifications as may come within the scope of the appended claims. 95

Having thus described my invention, what I claim as new and desire to secure by Letters Patent, is as follows:

1. A refrigerator comprising an ice compartment having a drain opening in the bottom thereof, a stationary receiver for water disposed below said drain opening, comprising a hinged side member, a removable receptacle disposed below said receiver adapted to receive the overflow of water therefrom, and means for lowering said hinged side to permit rapid discharge of water from said stationary receiver to said removable receptacle. 100 105

2. A refrigerator comprising an ice compartment having a drain opening in the bottom thereof, a stationary water receiver 110

disposed below said drain opening comprising a hinged side member, a flexible lining in said stationary receiver adapted to cover said hinged side and to rotate therewith when the latter is lowered for discharging water from said receiver, and mechanism operatively connected with said hinged side and pivotally mounted on said refrigerator comprising an operating handle adapted to be manipulated for lowering said hinged side.

3. A refrigerator comprising an ice compartment having a drain opening in the bottom thereof, a stationary water receiver disposed below said drain opening comprising a hinged side member, a flexible lining in said stationary receiver adapted to cover said hinged side and to rotate therewith when the latter is lowered for discharging water from said receiver, operating mecha-

nism comprising a shaft journaled on the bottom of said refrigerator, a lever fixed at an end on the middle portion of said shaft and pivotally attached at the other end to the hinged side of said receiver, an operating handle for rotating said lever for lowering said hinged side, and a spring mounted on said shaft for rotating the latter to raise said hinged side to its uppermost position. 25

4. A refrigerator comprising an ice chamber having a drain opening in the bottom wall thereof, a stationary receiver positioned below said drain opening to receive water therefrom, a removable receptacle disposed below said receiver, and means for controlling the flow of water from said receiver to said removable receptacle. 30 35

In testimony whereof I have affixed my signature.

THEODORE S. MORTON.
